INVENTOR.

Horace E. Britton,
by G. Schenck
Atty.

UNITED STATES PATENT OFFICE.

HORACE E. BRITTON, OF STOUGHTON, MASSACHUSETTS.

TOOL-HOLDER.

SPECIFICATION forming part of Letters Patent No. 516,294, dated March 13, 1894.

Application filed November 24, 1893. Serial No. 491,914. (No model.)

To all whom it may concern:

Be it known that I, HORACE E. BRITTON, a citizen of the United States, residing at Stoughton, in the county of Norfolk and State 5 of Massachusetts, have invented certain Improvements in Tool-Holders, of which the following is a full, clear, and exact description, reference being had to the accompanying drawings, making part of this specification, in which—

Figure 1 is a side elevation of a tool-holder constructed in accordance with my invention. Fig. 2 is a longitudinal section through the center of the same. Fig. 3 is a view of the 15 tool-holder with the cap removed showing the supernumerary tools in place around the central tool-holding socket-piece. Fig. 4 is a longitudinal section of the solid or rear portion of the handle with the supernumerary 20 tools removed therefrom.

My invention relates to that class of tool-holders having a metallic socket-piece projecting axially from the solid or rear portion of the handle, and adapted to receive the 25 shank of the tool which is clamped in place between the holding-jaws of said socket-piece over which is fitted a hollow conical cap or nut forming a portion of the handle, the solid or rear portion of said handle being provided 30 with a series of holes arranged circumferentially around it to receive the shanks of a set of supernumerary tools which extend up into the chamber formed between the hollow cap and the tool-holding socket-piece. As hitherto constructed, the inner end of this hollow 35 cap has been made to fit over upon the outside of the end of the solid or rear portion of the handle and slide freely thereon when turned to clamp or release the tool, and con- 40sequently when said cap was screwed down into place, a short chamber only was afforded which limited the distance that the supernumerary tools could project beyond the holes in the handle, it being undesirable to 45 increase the length of the hollow cap as this would render the handle too large and detract from its neat and compact appearance. This short chamber within the cap is how- 50ever objectionable, inasmuch as the blades or available portions of certain kinds of tools must necessarily be made quite short, and consequently soon become worn away by fre-

quent grinding, when they must be discarded as of no further use. To overcome this objection and increase the capacity of the tool-holder so that it will accommodate a set of tools with larger and longer blades without increasing either the length of the handle or that of the hollow cap, is the object of my invention, which consists in a handle having 55 the front end of its solid or rear portion provided with a circular recess extending around the tool-holding socket-piece and having at its bottom a series of holes arranged circumferentially around it for the reception of the 60 shanks of the tools, combined with a hollow cap, the inner end of which is adapted to enter and slide within said recess, whereby its edge is concealed and a neater appearance 65 presented, while the length of the chamber 70 within the cap is increased, as the entire length of said chamber is available for use and is not diminished by setting the cap down into place as is the case when its inner end fits over and slides upon the outside of the 75 solid or rear portion of the handle as first described.

In the said drawings, A, B, represent the two portions of the handle, the solid or rear part A being preferably composed of wood 80 and having the shank of a tool-holding socket piece D, which may be of any suitable or approved construction, driven axially therein as shown in Fig. 2, in such manner that it will be held firmly in place, said socket-piece 85 being provided with suitable ears or lugs b made integral therewith and projecting out into the wood to prevent the socket-piece from rotating independently of the handle. The part B consists of a tubular shell or cap 90 preferably composed of metal, its outer portion being of conical or bell shape and preferably provided at its extreme end with an internal screw thread forming a nut which is adapted to fit a corresponding thread on the 95 outer conical end of the socket-piece D, whereby the jaws c of the latter may be clamped tightly over the shank d of the tool E inserted between the same. I do not however limit myself to the employment of a tool-holding 100 socket-piece constructed as described, or to clamping the tool therein by means of a screw thread on the inside of the outer end of the hollow cap, as other devices may be employed

for clamping the tool in place within the end of the socket-piece without departing from the spirit of my invention. The axial passage *e* formed between the jaws *c* is preferably provided with a pin *f* driven into a hole bored in the solid portion of the socket-piece; said pin *f*, which is of slightly less diameter than that of the axial passage *e*, extending up some distance above the bottom of the slits 10, as shown in Fig. 2, and forming a solid rest or support for the base of the shank of the tool, said rest being at the proper distance from the outer ends of the jaws to accommodate a tool-shank of ordinary length.

15 Within the front end of the solid or rear part *A* of the handle is formed an annular recess *g* of any suitable depth, leaving a hub *h* around the socket-piece *D* as shown in Figs. 2 and 4 which hub is encircled by a metal ferrule *i* driven tightly thereover, whereby the splitting of the wood is prevented and the socket-piece held more firmly in place. At the bottom of this recess *g* are formed a series of holes *k* arranged circumferentially around 20 the same to receive the shanks of a set of supernumerary tools *l* which extend up into the chamber *m* formed between the hollow cap *B* and the socket-piece *D* as shown in Fig. 2. The diameter of the cylindrical portion *n* of 25 the cap *B* is such that its inner end will fit snugly within the circular recess *g* when turned down on the conical threaded end of the socket-piece to clamp the tool *E* in place between the jaws, the inner edge of the cap being thus concealed from view and a much 30 neater and more finished appearance thereby presented than where the cap is constructed to fit over and slide upon the outside of the end of the part *A* as has hitherto been the case. By thus forming a recess in the front 35 end of the part *A* for the reception of the inner end of the hollow cap *B* as described, I am enabled to materially increase the length of the chamber *m* without in the least increasing the length of the cap *B* or the part *A*, as 40 the entire length of the interior of the cap from its inner end 15 to the shoulder 20 can be utilized to hold the blades of the tools, whereas with the old construction the length 45 of this chamber within the cap was reduced to the extent that the cap slid over the outside of the front end of the part *A*, consequently with my improved construction the length of the blades of certain tools can be 50 increased so that they will last for a greater length of time under the wear due to frequent sharpening, and in this manner the capacity of a tool-holder of a given size can be largely increased so that it will take a set of 55 tools with larger and longer blades without

increasing the length of the handle or its cap or making them clumsy in appearance, a desideratum hitherto unattained in tool holders of this description; furthermore with my improved construction certain kinds of tools 65 such as saw-blades, flat reamers, &c., can be included among the other tools, which if made with short blades to fit within the shorter chamber of a tool holder of the old construction, would be of no practical value. 70

The annular recess *g*, is of much greater width than the thickness of the walls of the cylindrical portion *n* of the cap, and the circle described by the series of holes *k* lies within that of the interior of the said portion *n* of the cap, so that ample room is afforded within said recess *g*, for the lower portions of the tool blades, as is clearly shown in Fig. 2.

What I claim as my invention, and desire to secure by Letters Patent, is— 80

1. A tool holder consisting in a handle provided with a tool holding socket at its front end, and an annular recess in said front end concentric with said socket and provided in its base with a circular series of tool shank 85 apertures, and a hollow removable cap fitting over said socket and having a cylindrical body sliding at its inner end into said recess beyond or exterior to the said series of apertures; the walls of said cap being of less thickness than the width of said annular recess to allow the lower portions of the tool blades to enter said recess and thus permit the use of blades as much longer for a given length of cap and handle as the depth of the said recess, substantially as herein described. 90

2. A handle *A*, having a longitudinally extending tool-holding socket *D* at its front end and provided in said front end with an annular recess *g*, concentric with said holder, of a 100 width to receive the lower portions of tool blades and provided in its base with a circular series of tool shank apertures, and the cap *B* having a threaded aperture or nut to receive and operate the tool socket and provided with a hollow cylindrical body portion 105 *n* forming in connection with recess *g*, a tool holding chamber; the said recess receiving the lower end of the said cylindrical body beyond or exterior to the said apertures and of 110 a greater width than the thickness of the walls of said cylindrical portion, substantially as herein described.

Witness my hand this 20th day of November, A. D. 1893.

HORACE E. BRITTON.

In presence of—
P. E. TESCHEMACHER,
HARRY W. AIKEN.
